UNITED STATES PATENT OFFICE.

JAMES H. CAPLAN, OF BOSTON, MASSACHUSETTS.

TOOL FOR DEMOUNTABLE RIMS.

Application filed July 21, 1919. Serial No. 312,152.

To all whom it may concern:

Be it known that I, JAMES H. CAPLAN, a citizen of the United States, residing at Boston, in the county of Suffolk and State of Massachusetts, have invented a new and useful Improvement in Tools for Demountable Rims, of which the following is a specification, reference being had to the accompanying sheet of drawing, forming part thereof.

10 My invention relates to rim tools, particularly to such as are applicable for attaching and detaching demountable rims and tires to and from each other.

The object of the invention is to provide 15 a simple tool which is capable of doing work efficiently and with the least strain on the operator. To accomplish this result I employ gears for transmitting power to the working parts of the tool, and am thereby 20 enabled to operate the tool by a turning motion which is easy on the operator and which effectively manipulates the device.

A further object of the invention is to 25 provide a tool which is designed with a contracting and expanding feature, cooperating with a prying or jacking feature, for opening the joint of a split rim for contracting purposes or for expanding the rim and forcing a closure of the joint thereof, according 30 as may be desired.

With the above and other objects in view, the invention consists of the novel features of construction and the arrangement and combination of parts hereinafter more fully 35 described and set forth in the subjoined claims.

In order to illustrate my invention I have shown an embodiment thereof in the accompanying drawing, wherein:

40 Fig. 1 represents an elevational view showing my device associated with a rim for opening and contracting the same to free the tire therefrom;

Fig. 2 represents a plan view of the device as shown in Fig. 1;

Fig. 3 represents a sectional view taken on line 3—3 on Fig. 1;

Fig. 4 represents an enlarged part elevational and part sectional view of the gear casing member of the device with the cover plate thereof removed therefrom for showing the internal gears of the device;

Fig. 5 represents a similar view to Fig. 4 but shows the eccentric disc cover plate secured in place;

Fig. 6 represents a similar view to that

shown in Figs. 4 and 5, but shows the eccentric disc shifted to engage the operating gear with the clamping screw gear of the device instead of engaging with the jacking gear of the device, as shown in the preceding figures;

Fig. 7 represents a sectional view taken on line 7—7 on Fig. 5; and

Fig. 8 represents an elevational view of 65 the eccentric disc removed from the cover plate and showing the eccentric locking and shifting finger.

The terms employed herein are used in the generic and descriptive sense to designate 70 the elements illustrated, and are therefore not intended to be used as terms of limitation.

Like numerals refer to like parts throughout the several views of the drawing. 75

The numeral 10 represents an ordinary pneumatic tire mounted on the demountable rim 11 having the usual split joint 12.

15 represents the gear casing member of the device which is provided with the clamp-screw-bearing 16, the jack-screw threaded socket 17, and the stationary clamp lug 18. 19 represents the eccentric disc cover plate which is secured to said gear casing member 15 in any suitable manner, as by means of the screws 20, and is provided with the offset bore 21 of which "C" is the center and which has the angularly disposed locking slots 22 and 23 and the recessed locking finger section 24 cut therebetween, as shown in 90 Fig. 5. 25 represents the eccentric disc which is adapted to freely fit within the eccentric bore 21 and is provided on the outer side thereof with the shouldered flange 26 and on the inner side with the adjacently set retaining disc 27 which is suitably secured to the eccentric disc 25, as by means of the screw 28 shown in Fig. 8. 29 represents a radial slot cut in the eccentric member 25 which also projects through the outer flange 26 (Figs. 5 and 7), in which slot is 100 slidably fitted the L-shaped locking and shifting finger 30 which is acted against by the expansion spring 31 and forced into the locking slots 22 and 23 of the cover plate member 19 when brought into register therewith. 32 represents an offset bore provided in the eccentric disc 25 and plate 27, having the center "E" and forming the bearing for the operating gear 33 which has the stud 110 34 thereof rotatably mounted therein, as shown in Figs. 3 and 7. 35 represents a col-

lar which is keyed or pinned to the stud 34 for holding the same against end play in the eccentric disc, said stud 34 being preferably squared off on the projecting end 36 thereof for engaging the similarly shaped socket of the turning crank member 37, as shown in Figs. 1 and 3.

40 represents the jack-screw of the device which is provided with the key-way 41 and 10 fits the threaded socket 17 of the casing member 15. 42 represents the jack-screw-gear which is bored to freely fit over the jack-screw 40 and is provided with the key 43 which slidably fits within the key-way 41 15 of the jack-screw, as shown in Fig. 3. 44 represents a spacing tube which houses the jack-screw therein and serves to hold the jack-screw-gear 42 in place in the device. Said tube may be secured in the device in 20 any suitable manner, as by means of the retaining stud 45 shown in said Fig. 3.

50 represents the clamping-screw member of the device which is threaded at the projecting end 51 and rotatably mounted 25 at the shoulder section 52 thereof in the bearing 16 provided therefor in the casing member 15. 53 represents the clamping-screw-gear which is secured to the clamping-screw 50 in any suitable manner as by means 30 of the pin 54 for rotating therewith. 55 represents a movable block which threaded-ly engages with the threaded portion 51 of the clamp-screw 50 of the device (Figs. 1 and 2) and carries the retaining, gripping 35 jaw pins or studs 56 on the sides thereof, upon which are freely and pivotally mounted (with ample clearance) the gripping jaws 57. Said jaws 57 are preferably provided with the hooked ends, as shown, for 40 engaging the flanges of the rim 11 and are adapted to be clamped together in secured position with the rim by the clamping bolt 58 which threadedly engages with one of said jaws 57, the bolt being preferably pro- 45 vided with a head 59 which is similarly shaped and sized to that of the stud 36 to fit the socket of the crank 37 for permitting the use of the latter in connection therewith.

50 Similarly, the stationary clamping lug 18 is provided with the pins or studs 60 which pivotally carry the clamp jaws 61 which are also preferably hooked at the ends and provided with the clamping bolt 62 which 55 threadedly engages with one of the jaws 61 and freely fits the other, and has the shaped head 63, similar to that of the head 59, and stud 36 for fitting the socket of the turning crank member 37.

60 Having thus described the parts of my invention in detail, the manner in which the same may be operated is as follows:

First, it will be understood that the turning crank 37 is preferably detachable and 65 is adapted to fit the operating gear stud 36,

the clamping bolt head 59, or the clamping bolt 63, according as may be desired.

Secondly, the eccentric disc, which carries the operating gear rotatably mounted therein, is itself adapted to angularly turn 70 within the bore 21 provided therefor in the fixed cover plate 19 of the casing member 15, and in doing so permits the operating gear 33, which is carried thereby, to engage with either one or the other of the gears 75 42 or 53, and that said eccentric disc 25 may be locked into engaging position with either of said gears 42 or 53, as the case may be and according as may be desired, through the locking finger 30. 80

Thus, if it is desired to operate the clamp-screw 50, the operating gear is shifted to mesh with the clamp-screw-gear 53, as shown in Fig. 6, and the locking member 30 is locked in the slot 23. While if it is desired to operate the jack-screw 40, the operating gear 33 is brought into engagement with the jack-screw gear 42, as shown in Figs. 1, 3, 4 and 5, with the locking member 30 set in the slot 22, as there shown. The turning of the operating gear 33, through the turning of the crank 37 when said operating gear is so set with either of said gears 42 or 53, will rotate the selected gear according to the direction of rotation of 90 said turning crank 37. So that it will be understood that the turning of the jack-screw-gear 42 in one direction or the other will either feed the jack-screw 40 in or out of the casing member 15, according as may be desired, and also that the turning of the clamping-screw 50 in one direction or the other will cause the traveling block 55 to move along said clamping-screw in one direction or the other, according as may be desired. 100

Thus it will be understood that the tool is detachably coupled with the rim to be handled thereby by means of the pair of gripping jaws 61 and 57 which engage and grip the opposite flanges of the rim on either side of the split joint thereof, as shown in Fig. 1. 110

It will be here noted that it is preferred (without being limited thereto) to make the casing supported, gripping jaws 61 shorter than the anchoring jaws 57, which are supported on the movable block 55, for bringing the jack-screw socket 17 of the casing member 15 nearer to the rim 11, as shown in Fig. 1. It is also preferable to position said shorter gripping jaws nearer to the split 120 of the rim, as shown in said Fig. 1. 115

With the gripping jaws of the device thus secured to the rim, the device may then be manipulated according as the particular needs of the rim may require, depending upon the type of joint of the particular rim. If the rim has the so-called interlocking joint the first operation would be to expand the rim, which may be accomplished by free- 125 130

ing the jack-screw 40 from the rim and causing the movable-block 55 to move towards the outer and projecting end of the clamping-screw 50. This spreading or expansion 5 feature would result from engaging the operating gear 33 with the gear 53, as shown in Fig. 6, and turning the crank 37 in the direction to feed the screw 50 so that said block 55 would be forced to move towards 10 the end of said clamping member 50, as suggested. With the rim joint thus spread open, the next operation of the tool would be to cause the end of the rim engaging the short, gripping 15 jaw of the tool to overlap the other end of the rim. To do so the operating gear 33 should be shifted to the engaging position with the jack-screw-gear (shown in Figs. 1 and 3, 4 and 5), then the turning crank 37 20 should be turned to bring the jack-screw 40 into frictional engagement with the rim, as shown in Fig. 1. The turning of said crank 37 will soon jack up the short clamp 61 so that thereafter by contracting the tool 25 through again operating the clamp-screw in the opposite direction this time, the end of the rim held by said short clamp will overlap the other end and allow the rim to contract. So to effect the contracting feature, 30 shift the operating gear to engage with the clamping-screw-gear 53 and turn the crank 37, this time to cause the movable block 55 to approach the casing member 15. The tool in this contracting operation will 35 contract the rim and allow for the ready and easy removal of the tire 10 therefrom.

In a similar manner it will be understood 40 that the rim may be replaced with the tire again, and any type of split rim may thus be handled by the tool easily and efficiently. It will also be understood that the work of manipulating the tool is reduced to a minimum, so far as strain to the operator is concerned, and that the rapidity of operation, 45 results and power produced by the tool are absolutely reliable and at the point of maximum efficiency.

It will here be noted that the clamp-screw 50 gripping member 57 serves to anchor the device to the rim, while the casing carried gripping member manipulates the overlapping end of the rim.

It will be here observed that the gears 55 used in the device are preferably beveled as the miter gears shown, and that the arrangement of the same in the device allows the crank-lever 37 to be operated substantially in the plane of the rim and tire, and render the tool convenient to handle and operate. It will also be observed that the center "E" of the operating gear, when the eccentric disc 25 is shifted in the bore 21 of the cover member 19, moves about the center 60 "C" of said eccentric disc 25 on the circle "X" of which "C" is also the center as shown

in Figs. 4, 5 and 6, and that said center "E" in either one or the other of its shifted positions lies on either one or the other of the lines of axis of the gears engaging with the operating gear. 70

While the preferred embodiments of my invention have been described, in detail, it will be understood that I do not wish to be limited to the particular construction set forth, since various changes in the form, 75 material, proportions, and arrangement of parts, and in the details of construction may be resorted to without departing from the spirit and scope of the invention, or destroying any of the advantages contained in 80 the same heretofore described and defined in the subjoined claims.

Having thus described my invention in detail, what I claim as new is:

1. A rim tool having a pair of gripping 85 members adapted to be detachably secured to the rim flanges with the split of the rim positioned therebetween; intermediate jacking means adapted to engage with the rim for distorting an end of the rim from its butting position at the joint; means for changing the spread between the pair of gripping members for contracting or expanding the rim; and common operating 90 means adapted to be shifted into working relation with either said jacking or gripping member spread changing means for operating either of said means at will. 95

2. A rim tool having universal gripping 100 members adapted to detachably engage the opposite flanges of a rim at either side of the split joint thereof; a coupling member supporting said gripping members and adapted to contract or expand the spread therebetween; an intermediate jacking member adapted to control the position of said coupling member in relation to the rim; and common operating means adapted to operate 105 said coupling member and said jacking member independently of each other. 110

3. In a rim tool, a casing member having 115 a clamping-screw bearing, a threaded jack-screw socket and a gripping member supporting lug; a rim gripping member pivotally secured to said gripping member supporting lug; a jack-screw fitted within said socket and provided with a gear within said casing, adapted to feed said jack-screw in either direction within said socket; a clamping-screw rotatably mounted within said bearing of said casing member also provided within said casing with a gear adapted to rotate same; a movable block member adapted to threadedly engage said clamping-screw for riding thereon and provided with a second rim gripping member pivotally secured thereto and carried thereby; and a cover member adapted to be secured to said casing member and provided with gear 120 means adapted to engage said gears, within 125

said casing member, for driving and operating same.

4. In a rim tool, a casing member having a clamping-screw bearing, a threaded jack-screw socket and a gripping member supporting lug; a rim gripping member pivotally secured to said gripping member supporting lug; a jack-screw fitted within said socket and provided with a gear within said casing, adapted to feed said jack-screw in either direction within said socket; a clamping-screw rotatably mounted within said bearing of said casing member also provided within said casing with a gear adapted to 10 rotate same; a movable block member adapted to threadedly engage said clamping-screw for riding thereon, and provided with a second rim gripping member pivotally secured thereto and carried thereby; and a cover member adapted to be secured to said casing member and provided with an eccentric disc supported therein, having an eccentrically positioned gear member rotatably mounted therein and adapted to be shifted by the 15 angular turning of said eccentric disc to engage with either one or the other of said gears within the casing member for accordingly operating the jack-screw or the clamping-screw.

5. In a rim tool, a casing member having a clamping-screw bearing, a threaded jack-screw socket and a gripping member supporting lug; a rim gripping member pivotally secured to said gripping member supporting lug; a jack-screw fitted within said socket and provided with a gear within said casing, adapted to feed said jack-screw in either direction within said socket; a clamping-screw rotatably mounted within said 20 bearing of said casing member also provided with a gear, within said casing, adapted to rotate said clamping-screw; a movable block member adapted to threadedly engage said clamping-screw for riding thereon, and provided with a second rim gripping member pivotally secured thereto and carried thereby; a cover member adapted to be secured to said casing member and provided 25 with an eccentric disc supported therein, having an eccentrically positioned gear member rotatably mounted therein and adapted to be shifted by the angular turning of said eccentric disc to engage with either one or the other of said gears within the casing member for accordingly operating the jack-screw or the clamping-screw.

6. In a rim tool, a casing member having a clamping-screw bearing, a threaded jack-screw socket and a gripping member supporting lug; a rim gripping member pivotally secured to said gripping member supporting lug; a jack-screw fitted within said socket and provided with a gear within said casing, adapted to feed said jack-screw in either direction within said socket; a clamping-screw rotatably mounted within said 30 bearing of said casing member also provided with a gear, within said casing, adapted to rotate said clamping-screw; a movable block member adapted to threadedly engage said clamping-screw for riding thereon, and provided with a second rim gripping member pivotally secured thereto and carried thereby; a cover member adapted to be secured to said casing member and provided 35 with an eccentric disc supported therein, having an eccentrically positioned gear member rotatably mounted therein and adapted to be shifted by the angular turning of said eccentric disc to engage with either one or the other of said gears within the casing member for accordingly operating the jack-screw or the clamping-screw.

7. In a rim tool, a casing member having a clamping-screw bearing, a threaded jack-screw socket and a gripping member supporting lug; a rim gripping member pivotally secured to said gripping member supporting lug; a jack-screw fitted within said socket and provided with a gear within said casing, adapted to feed said jack-screw in either direction within said socket; a clamping-screw rotatably mounted within said 40 bearing of said casing member also provided with a gear, within said casing, adapted to rotate said clamping-screw; a movable block member adapted to threadedly engage said clamping-screw for riding thereon, and provided with a second rim gripping member pivotally secured thereto and carried thereby; a cover member adapted to be secured to said casing member and provided 45 with an eccentric disc supported therein, having an eccentrically positioned gear member rotatably mounted therein and adapted to be shifted by the angular turning of said eccentric disc to engage with either one or the other of said gears within the casing member for accordingly operating the jack-screw or the clamping-screw.

with an eccentric opening supporting a gear disc therein, having an eccentrically positioned gear member rotatably mounted therein, and adapted to be shifted by the angular turning of said gear supporting disc to engage with either one or the other of said gears within the casing member for accordingly operating the jack-screw or the clamping-screw; and means for locking said eccentric disc in either of its shifted positions.

6. In a rim tool, a casing member having a clamping-screw bearing, a threaded jack-screw socket and a gripping member supporting means; a rim gripping member pivotally secured to said gripping member supporting means; a jack-screw fitted within said socket and provided with a gear within said casing, adapted to feed said jack-screw in either direction within said socket; a clamping-screw rotatably mounted within said bearing of said casing member also provided within said casing with a gear adapted to rotate said clamping screw; a movable block member adapted to threadedly engage said clamping-screw for riding thereon and provided with a second rim gripping member pivotally secured thereto and carried thereby; a cover member adapted to be secured to said casing member and provided with an eccentric disc opening having locking slots and supporting a gear disc in said opening, said disc having a latching member adapted to engage with said locking slots and an eccentrically positioned gear member rotatably mounted therein, adapted to be carried by said disc into or out of engagement with either of said jack or clamping screw gears; and means for operating said disc gear for driving the selected gear engaging therewith. 60 65 70 75 80 85 887

In testimony whereof, I hereunto set my ⁹⁰ hand this 18th day of July, 1919.
